United States Patent Office.

ANTHONY VAN HAAGEN, OF PHILADELPHIA, PENNSYLVANIA, ASSIGNOR
TO McKEONE, VAN HAAGEN & CO.

Design No. 4,534, dated December 20, 1870.

DESIGN FOR A BLOCK OF SOAP.

The Schedule referred to in these Letters Patent and making part of the same.

I, ANTHONY VAN HAAGEN, of Philadelphia, county of Philadelphia, State of Pennsylvania, have invented or produced a Design for a Cake of Soap, of which the following is a specification.

The figure in the accompanying drawing represents my design for a cake or block of soap.

The opposite sides, *a*, of the cake are parallel and at right angles to the ends *b*, the edges *z z* of the latter being curved to conform to the shape of the curved faces *d* of the cake, which curved faces join the sides and ends abruptly, so as to form the sharp angles and corners plainly shown in the drawing.

I claim—

The design for a block or cake of soap, substantially as described, and as represented in and by the accompanying drawing.

In testimony whereof I have signed my name to this specification in the presence of two subscribing witnesses.

ANTHONY VAN HAAGEN.
